UNITED STATES PATENT OFFICE

139,386

DESIGN FOR A TOBOGGAN

James A. Worden, Portage, Wis.

Application March 13, 1944, Serial No. 112,893

Term of patent 7 years

(Cl. D14—24)

To all whom it may concern:

Be it known, that I, James A. Worden, a citizen of the United States, residing at Portage, in the county of Columbia and State of Wisconsin, have invented a new, original, and ornamental Design for Toboggan, of which the following is a specification, reference being had to the accompanying drawing, forming part thereof.

In the drawing:

Figure 1 is a top view of a toboggan showing my new design; and

Figure 2 is a side perspective view thereof.

I claim:

The ornamental design for a toboggan, as shown.

JAMES A. WORDEN.
